(57) **CLAIM**

The ornamental design for a handle for use with a micro surgical knife, as shown and described.

DESCRIPTION

This application is related to U.S. Provisional application Ser. No. 61/322,784 filed Apr. 9, 2010, entitled Micro Surgical Knife With Safety Feature and U.S. Utility patent application Ser. No. 12/872,339, entitled Micro Surgical Knife With Safety Feature filed contemporaneously with this application, still pending. The contents of those applications are incorporated by reference herein in their entirety.

FIG. 1 is a perspective view of the retracted position of the guard in a first embodiment of our new design;
FIG. 2 is a perspective view of the extended position of the guard in a first embodiment of our new design
FIG. 3 is a side view of the extended position of the guard in a first embodiment of our new design;
FIG. 4 is a top view of the extended position of the guard in a first embodiment of our new design;
FIG. 5 is bottom view of the extended position of the guard in a first embodiment of our new design;
FIG. 6 is a perspective view of the retracted position of the guard in a second embodiment of our new design;
FIG. 7 is a perspective view of the extended position of the guard in a second embodiment of our new design
FIG. 8 is a side view of the extended position of the guard in a second embodiment of our new design;
FIG. 9 is a top view of the extended position of the guard in a second embodiment of our new design;
FIG. 10 is bottom view of the extended position of the guard in a second embodiment of our new design;
FIG. 11 is a perspective view of the retracted position of the guard in a third embodiment of our new design;
FIG. 12 is a perspective view of the extended position of the guard in a third embodiment of our new design;
FIG. 13 is a side view of the extended position of the guard in a third embodiment of our new design;
FIG. 14 is a top view of the extended position of the guard in a third embodiment of our new design;
FIG. 15 is bottom view of the extended position of the guard in a third embodiment of our new design;
FIG. 16 is a perspective view of the retracted position of the guard in a fourth embodiment of our new design;
FIG. 17 is a perspective view of the extended position of the guard in a fourth embodiment of our new design
FIG. 18 is a side view of the extended position of the guard in a fourth embodiment of our new design;
FIG. 19 is a top view of the extended position of the guard in a fourth embodiment of our new design; and,
FIG. 20 is bottom view of the extended position of the guard in a fourth embodiment of our new design.
The portions of the handle for use with a micro surgical knife which are shown in broken lines are for illustration purposes only and form no part of the claimed design.
